DEVICE FOR FORMING HELICAL COILS

Charles Antheny, Philadelphia, Pa.

Application March 1, 1946, Serial No. 651,412

6 Claims. (Cl. 153—67)

(Granted under the act of March 3, 1883, as
amended April 30, 1928; 370 O. G. 757)

1

This invention relates to spring winding devices and more particularly to devices for fashioning helical springs.

Objects of the invention are to provide improved manually operable devices for fashioning helical springs of either the tension or the compression type; to provide improved devices for fashioning helical springs from lengths of wire in which provision is made for accommodating wire of any desired diameter within the range of the device; to provide improved spring winding devices in which provision is made for varying the diameter of the helix formed and the pitch or spacing between adjacent coils of the helix; and to provide improved spring winding devices of the character described and for the purposes set forth.

In accomplishing these and other objects of the present invention, I have provided improved details of structure, a preferred form of which is shown in the accompanying drawing, wherein:

Fig. 1 is a side elevational view, partly in section, of a spring winding device embodying the features of the present invention;

Fig. 2 is a rear elevational view of the spring winding device shown in Fig. 1.

Referring more in detail to the drawing:

The spring winding device of the present invention comprises a body member 1. The latter includes a depending shank 2, adapted to be gripped in a vise or other clamping mechanism to support the device, and a disc-like portion 3, preferably formed integrally with said shank. A series of apertures 4 of varying diameters are formed through said disc-like portion.

The apertures 4 are adapted to receive cooperating mandrels 5. Preferably a plurality of such mandrels of varying diameters are provided corresponding to the varying diameters of the apertures 4. In fashioning a spring, a mandrel 5 of diameter equal to the inside diameter of the spring is chosen and inserted through the aperture 4 of similar diameter.

A circular spacing plate 7 having an outer periphery 6 is rotatably mounted at the center of the disc-like portion 3 of the body member by a means hereinafter described. It will be seen that the inner edges of the apertures 4 are spaced substantially equidistantly externally of the periphery 6 of said spacing plate by a comparatively slight amount. The peripheral face of the plate thus clears the surface of any mandrel 5 inserted through its cooperating aperture 4 by a fixed distance.

The thickness of the spacing plate 7 varies throughout the circumference, the plate 7 provid-

2

ing a helical surface tapering circumferentially to a thin-edged leading end portion 8 from a trailing end portion 9 of maximum thickness (Fig. 1). The plate 7 is rotatably adjustable to bring the portion of the helical surface thereof of any desired thickness contiguous to the mandrel 5. The portion of plate 7 adjacent the mandrel fits between adjacent coils of a wire 10 being wound about the mandrel to form a spring. A notch 11 is preferably formed in the edge of the plate 7 where the leading end portion 8 and the trailing end portion 9 come together. The plate 7 is rotated to a position in which said notch 11 is adjacent the mandrel 5 when it is desired to wind a spring in which adjacent coils contact each other.

The forward face of the plate 7 is adjustably maintained in spaced relation from the rearward face of the body 1, the space therebetween being designated 12 and being adjustable as to thickness to receive wire of desired diameter. An outer bushing 13 is threadedly engaged through a central bore in the disc-like portion 3 of the body member 1 and the rearward face of said bushing 13 engages the forward face of the plate 7 to retain the latter at the desired spacing from the rearward face of the body member 1.

Wire 10 to be wound to form a spring may be tensioned by looping it around the external periphery of the bushing 13. Preferably a pin 14 protrudes from the rearward face of the body member 1 about which wire 10 of relatively fine diameter may be additionally looped to increase the tension therein.

The outer bushing 13 is maintained in adjusted position by a lock nut 15 which preferably has apertures 16 in its periphery to receive a wrench or other suitable tool to be used in adjusting the lock nut 15.

The spacing plate 7 is rotatably supported on a bearing member 17 which is slightly eccentric and so functions to position the periphery of plate 7 close to the selected mandrel 5. Said bearing member 17 has a rearwardly projecting spindle 18, a forwardly projecting threaded spindle 19, a shoulder 20 and a flange 21, all preferably formed integrally. A lock nut 22, preferably having apertures 23 in its periphery, is threadedly engaged with the forwardly projecting spindle 19.

The spacing plate 7 has a central portion 24 that is clamped between the flange 21 and the outer bushing 13. The rearward face of the plate 7 preferably is recessed, as indicated at 25, to receive said flange 21.

An inner bushing 28 is threadedly engaged 55 within the outer bushing 13 and has an axial bore

27 therethrough and a counter-bored portion 26 at the rearward end. The axial bore 27 receives the forwardly extending spindle 19, hereinbefore referred to, and the counter-bored portion 26 receives the shoulder 20. A lock nut 29 is threadedly engaged with said inner bushing 28 on the portion thereof that extends beyond the outer bushing 13. The setting of the spacing plate 7 may be varied by loosening the lock nut 22 and rotating the plate 7 without disturbing other settings of the device.

A handwheel 30, preferably knurled or notched, as indicated at 31, is pinned or otherwise fixedly engaged with the rearwardly extending spindle 18 of the bearing member 17 and has an inwardly extending portion that preferably contacts the rearward face of the flange 21 of said bearing member 17 within the recess 25 of the spacing plate 7. The handwheel 30 may be employed to rotate the plate 7 on loosening of the lock nut 22.

Preferably the spacing plate 7 has a rearwardly extending boss 32 having peripheral apertures 33 to receive a suitable tool for direct adjustment of the plate 7 when greater force is required than can be imparted through the handwheel 30.

A handle member 34 is provided for the mandrel 5 and has a plurality of apertures 35 for receiving mandrels of any desired diameter. The selected mandrel 5 is secured within the handle member by use of a set screw 36. Preferably the outer end of the handle member 34 has a hand grip 37 rotatably secured thereto.

A diametric notch or groove 38 is preferably formed in the rearward end face of the mandrel 5 for receiving and securing the end of the wire 10 during the fashioning of a spring therefrom.

The operation of a spring winding device constructed as described is as follows:

A mandrel 5 is selected having a diameter equivalent to the desired inside diameter of the spring to be made and is secured in the appropriate aperture 35 in the handle member 34 and inserted through the appropriate aperture 4 in the body member 1.

The lock nut 15 is loosened and the outer bushing 13 is adjusted to set the space 12 equal to the diameter of wire to be employed and said lock nut is then retightened. The lock nut 22 is loosened and the spacing plate 7 is rotated to bring the portion thereof having thickness equivalent to the desired spacing between adjacent coils of the spring contiguous to the mandrel 5.

Wire 10 is fed into the space 12 and the end thereof fixed in the notch 38 in the end of the mandrel. If desired, the wire 10, may be additionally looped about the pin 14.

The handle 34 is rotated, thus rotating the mandrel 5. The wire 10 is wound therearound to form a helical spring. The edge of the spacing plate passes between adjacent coils and determines their spacing or the pitch of the spring so formed. The winding of the wire 10 on the mandrel 5 feeds the latter through the aperture 4 so that a continuous coiled spring is formed. Since the winding takes place close to the support, deflection of the mandrel and malformation of the spring is prevented.

The setting of the spacing plate 7 may be varied during a winding operation, if it is desired to form a spring having portions of different pitch, or if it is desired to form more than one spring during a single operation.

Normally, compression type helical springs have greater pitch than tension type springs. It 75

is seen that, since pitch may be varied as desired when the device of the present invention is used, it is possible to wind either a compression spring or a tension spring.

5 While I have shown but a single embodiment of the present invention, it is obvious that the device is subject to modification without departing from the spirit of the invention. Therefore, I do not wish to be limited by the disclosure set forth, but only by the scope of the claims.

The invention described herein may be manufactured and used by or for the Government of the United States of America for governmental purposes without the payment of any royalties thereon or therefor.

15 What is claimed is:

1. A device for forming helical coils comprising a body member arranged to be supported and having a plurality of different sized cylindrical apertures extending substantially circumferentially about a center point, a circular spacing plate formed with a single helical surface for determining coil pitch, said plate having a notch between the leading and trailing ends of said helical surface, means for rotatably mounting said spacing plate within the inner circumference defined by said plurality of apertures on said body member and in spaced relation to said body member, said mounting means including a cylindrical portion extending across the space between said body member and said spacing plate, the helical surface on said spacing plate being on the side remote from said body member, said different sized apertures each being arranged to selectively receive a suitably sized rotatable cylindrical mandrel to which a wire may be secured and wound thereabout to form a coil, the wire being passed around the cylindrical portion of said mounting means between said spacing plate and said body member to be suitably tensioned and through the spacing plate notch to form either a closed coil or, over any selected portion of the helical surface of said spacing plate, to form an open coil of a desired pitch.

2. A device for forming helical coils comprising a body member arranged to be supported and having a plurality of different sized cylindrical apertures extending substantially circumferentially about a center point, a circular spacing plate formed with a single helical surface for determining coil pitch, said plate having a notch between the leading and trailing ends of said helical surface, means for rotatably mounting and adjusting said spacing plate within the inner circumference defined by said plurality of apertures on said body member in spaced relation to said body member, said mounting and adjusting means including a cylindrical portion extending across the space between said body member and said spacing plate, the helical surface on said spacing plate being on the side remote from said body member, said different sized apertures each being arranged to selectively receive a suitably sized rotatable cylindrical mandrel to which a

50 wire may be secured and wound thereabout to form a coil, the wire being passed around the cylindrical portion of said mounting means between said spacing plate and said body member to be suitably tensioned and through the spacing plate notch to form either a closed coil or, over any selected portion of the helical surface of said spacing plate, to form an open coil of a desired pitch.

55 3. A device for forming helical coils comprising a body member arranged to be supported and

having a plurality of different sized cylindrical apertures extending substantially circumferentially about a center point, a circular spacing plate formed with a single helical surface for determining coil pitch, said plate having a notch between the leading and trailing ends of said helical surface, means for rotatably and eccentrically mounting and adjusting said spacing plate within the inner circumference defined by said plurality of apertures on said body member and in adjustable spaced relation to said body member, said mounting and adjusting means including a cylindrical portion extending across the space between said body member and said spacing plate, the helical surface on said spacing plate being on the side remote from said body member, said different sized apertures each being arranged to selectively receive a suitably sized rotatable cylindrical mandrel to which a wire may be secured and wound thereabout to form a coil, the wire being passed around the cylindrical portion of said mounting means between said spacing plate and said body member to be suitably tensioned and through the spacing plate notch to form either a closed coil or, over any selected portion of the helical surface of said spacing plate, to form an open coil of a desired pitch.

4. A device for forming helical coils comprising a body member arranged to be supported and having a plurality of different sized cylindrical apertures extending substantially circumferentially about a center point, a circular spacing plate formed with a single helical surface for determining coil pitch, said plate having a notch between the leading and trailing ends of said helical surface, means for rotatably mounting and adjusting said spacing plate within the inner circumference defined by said plurality of apertures on said body member in spaced relation to said body member, said mounting and adjusting means including a cylindrical portion extending across the space between said body member and said spacing plate, said mounting and adjusting means comprising a spindle extending through substantially said center point through said body member, bushing means adjustably mounted in said body means, the outer end surface of said bushing means providing said cylindrical portion extending to said spacing plate, a spindle extending through said bushing means, an enlarged bearing member integrally formed on said spindle arranged to abut against one end of said bushing means, a nut threaded on said spindle at the other end of said bushing means to lock said spindle in said bushing means, said spacing plate bearing on said bearing and abutting said bushing means, means on said spindle abutting on said spacing plate on the side remote from said bearing means, the helical surface on said spacing plate being on the side remote from said body member, said different sized apertures each being arranged to selectively receive a suitably sized rotatable cylindrical mandrel to which a wire may be secured and wound thereabout to form a coil, the wire being passed around the cylindrical portion of said mounting means between said spacing plate and said body member to be suitably tensioned and through the spacing plate notch to form either a closed coil or, over any selected portion of the helical surface of said spacing plate, to form an open coil of a desired pitch.

5. A device for forming helical coils comprising a body member arranged to be supported and having a plurality of different sized cylindrical

apertures extending substantially circumferentially about a center point, a circular spacing plate formed with a single helical surface for determining coil pitch, said plate having a notch between the leading and trailing ends of said helical surface, means for rotatably and eccentrically mounting and adjusting said spacing plate within the inner circumference defined by said plurality of apertures on said body member and in adjustable spaced relation to said body member, said mounting and adjusting means including a cylindrical portion extending across the space between said body member and said spacing plate, said mounting and adjusting means comprising a spindle extending through substantially said center point through said body member, bushing means adjustably mounted in said body means, the outer end surface of said bushing means providing said cylindrical portion extending to said spacing plate, a spindle extending through said bushing means, an enlarged slightly eccentric bearing member integrally formed on said spindle arranged to abut against one end of said bushing means, a nut threaded on said spindle at the other end of said bushing means to lock said spindle in said bushing means, said spacing plate bearing on said eccentric bearing and abutting said bushing means, means on said spindle abutting on said spacing plate on the side remote from said bearing means, the helical surface on said spacing plate being on the side remote from said body member, said different sized apertures each being arranged to selectively receive a suitably sized rotatable cylindrical mandrel to which a wire may be secured and wound thereabout to form a coil, the wire being passed around the cylindrical portion of said mounting means between said spacing plate and said body member to be suitably tensioned and through the spacing plate notch to form either a closed coil or, over any selected portion of the helical surface of said spacing plate, to form an open coil of a desired pitch.

6. A device for forming helical coils comprising a body member arranged to be supported and having a plurality of different sized cylindrical apertures extending substantially circumferentially about a center point, a circular spacing plate formed with a single helical surface for determining coil pitch, said plate having a notch between the leading and trailing ends of said helical surface, means for rotatably and eccentrically mounting and adjusting said spacing plate within the inner circumference defined by said plurality of apertures on said body member and in adjustable spaced relation to said body member, said mounting and adjusting means including a cylindrical portion extending across the space between said body member and said spacing plate, said mounting and adjusting means comprising a spindle extending through substantially said center point through said body member, bushing means adjustably mounted in said body means, said bushing means consisting of an outer bushing threaded through said body member, an inner bushing threaded through said outer bushing, a nut for locking said outer bushing to said inner bushing, the outer end surface of said bushing means providing said cylindrical portion extending to said spacing plate, a spindle extending through said bushing means, an enlarged slightly eccentric bearing member integrally formed on said spindle arranged to abut against one end of said bushing means, a nut threaded on said

spindle at the other end of said bushing means to lock said spindle in said bushing means, said spacing plate bearing on said eccentric bearing and abutting said bushing means, means on said spindle abutting on said spacing plate on the side remote from said bearing means, and means for controllably rotating said eccentric bearing of said spindle, the helical surface on said spacing plate being on the side remote from said body member, said different sized apertures each being arranged to selectively receive a suitably sized rotatable cylindrical mandrel to which a wire may be secured and wound thereabout to form a coil, the wire being passed around the cylindrical portion of said mounting means between said spacing plate and said body member to be suitably ten-

sioned and through the spacing plate notch to form either a closed coil or, over any selected portion of the helical surface of said spacing plate, to form an open coil of a desired pitch.

CHARLES ANTHONY.
